UNITED STATES PATENT OFFICE.

ANDREW GRAYDON, OF LOS ANGELES, CALIFORNIA.

GARMENT CLASP.

Application filed May 24, 1921. Serial No. 472,103.

To all whom it may concern:

Be it known that I, ANDREW GRAYDON, a citizen of the United States, residing at Los Angeles, in the county of Los Angeles and 5 State of California, have invented a new and useful Garment Clasp, of which the following is a specification.

An object of this invention is to provide a garment clasp which is cheap, strong, simple 10 and easily manufactured, which will hold the garment securely with minimized likelihood of tearing the same under strains.

Another object of the invention is to make provision whereby the clasp will be held in 15 clasping position with minimized liability of being accidentally unfastened.

The invention comprises a garment clasp constructed of sheet metal having clasping heads formed with marginal flanges adapted 20 to frictional cushions or pads, between which the material to be held is clasped, thus to guard against injury to the garment, and thus to insure a firm frictional hold without endangering the material held.

25 Another feature of the invention is the provision of shanks for said heads respectively, the shanks being provided with a plurality of longitudinal ridges, the central ridge sloping from its ends to an inter-

30 mediate swell above the other ridges. A securing loop is provided sliding along said shanks to force the heads toward each other or to release said heads; and said loop will be held by the swells of said ridges when 35 slid to the gripper end of the shanks and will not be likely to become accidentally loosened or slid toward the other end.

Other objects, advantages and features of 40 invention may appear from the accompanying drawing, the subjoined detail description and the appended claims.

The accompanying drawing illustrates the invention.

Figure 1 is an enlarged perspective view 45 of a clasp closed and constructed in accordance with this invention.

Fig. 2 is a closed edge view of the same further enlarged.

Fig. 3 is a longitudinal section on line x^3 , 50 Fig. 1.

Fig. 4 is an open edge view of the same.

Fig. 5 is a cross section on line x^5 , Fig. 1.

Fig. 6 is a view in practical size, of the blank from which the grippers and shanks and spring connection are stamped up. 55

Fig. 7 is a view of the stamping on same scale as Fig. 6.

Fig. 8 is a view of the compressing loop detached.

The clasp is constructed of a stamping 60 which comprises a central eye 1, two longitudinally corrugated shanks 2, each terminating in gripping heads 3, which provide lateral extensions 4 at the sides of the shank. Said gripping heads are stamped up at the 65 edges to form flanges 5 with an enclosed recess 6 in which a frictional cushion as the rubber pads 7 are seated and held in place by the flanges, the pads extending beyond the flanges and forming gripping surfaces. 70 The shanks are shown each provided with a central ridge 8 having an intermediate swell 9 and being reduced in height at ends 10, 11 and straight unswelled ridges 8' one on each side of the central ridge 8. The stamping 75 is of spring sheet metal and is bent exactly midway between the heads or grippers 3 so that the shanks form equal radial arms so as to adapt the gripping heads to be pressed together. The shanks are normally held 80 apart by spring tension.

The compressing loop 12 is adapted to tightly fit upon the shanks when said loop encircles the shanks at the gripping heads and the intermediate portions of the shanks 85 are spaced apart so that their inner faces will be pressed toward each other by the loop engaging the swell 9 of the central ridge 8 when it is slid along the shanks. After the loop has been positioned at the 90 outer ends of the shanks or in gripping position, the loop then being at the end 11 of the central ridge 8 which end is reduced in height from the swell 9 allows the shanks to spring apart; and in this way the loop is 95 firmly held at rest against the heads when so positioned, and the likelihood of the gripping heads 3 becoming accidentally unfastened is minimized due to the action of the swell 9 bearing against the loop and 100 tending to force the loop into gripping position.

In practice after the eye has been formed and the loop placed on the shanks the usual

attaching link 14 is swiveled to the eye 1 by inserting its terminals, not shown, into the eye and then setting the link in place in the usual way. The clasp is then ready for 5 use.

I claim.

1. A clasp comprising an eye, resilient shanks extending from said eye and normally spread apart and having corrugations 10 that extend therealong, and that slope toward the ends of said shanks, heads on said shanks, and means cooperating with said sloping corrugations on said shanks for forcing said heads toward each other.

15 2. A clasp comprising resilient, normally diverging shanks secured together at one end and provided with longitudinally extending ridges reduced from an intermediate portion toward both ends, heads on the free 20 ends of said shanks having portions extending laterally from said shanks, and provided with gripping surfaces; and a loop sliding on the shank and ridges for forcing the heads together.

25 3. A clasp comprising substantially flat resilient normally divergent shanks connected at one end by an eye and having longitudinally extending ridges thereon, one of which tapers toward both ends from an 30 elevated central swell; heads on the other ends of said shanks, portions of which extend laterally from the shanks, flanges around the edges of said heads; resilient material filling the recesses formed by said 35 flanges and a ring on said shanks cooperating with said ridges to force the heads together.

4. A clasp comprising two resilient shanks secured together at one end and each terminating 40 at the other end in a head, a ridge extending longitudinally of one shank and being centrally swelled and tapering toward both ends and a loop slidable on said shanks and ridge to force the heads together.

45 5. A clasp comprising resilient shanks secured together at one end and each terminating at the other end in a head, a central

ridge and side ridges on said shanks, the central ridge rising at its mid point above 50 the side ridges at the mid point of said side ridges and tapering toward the ends of said side ridges, and a collar slidable on said shanks.

6. A clasp comprising resilient shanks secured together at one end and each terminating 55 at the other end in a head, resilient material on the inner surface of each head, a central ridge and side ridges on said shanks, the central ridge rising above the 60 mid point of each of said side ridges and tapering towards the ends of said side ridges, and a collar slidable on said shanks.

7. A clasp comprising resilient shanks secured together at one end and each terminating 65 at the other end in a head, each shank being provided with side ridges of uniform height throughout their length and a central ridge rising at its mid point above the 70 height of the side ridges and tapering toward its ends, and a loop on said shanks, cooperating with said ridges to force the heads together.

8. A clasp comprising resilient shanks secured together at one end and each terminating 75 in a head at the other end, a longitudinal ridge on said shanks which is reduced in height from its center toward its ends, and means engaging said ridge and adapted to slide therealong to bring said heads into 80 and release said heads from gripping engagement.

9. A clasp comprising shanks normally spaced apart by spring tension, gripping means on said shanks, a longitudinal ridge 85 on said shanks that has an intermediate swell, and means adapted to engage said ridge to force and hold said gripping means in gripping position.

In testimony whereof, I have hereunto set 90 my hand at Los Angeles, California, this 17th day of May, 1921.

ANDREW GRAYDON.
